YARN SHED TESTING MACHINE

Robert J. Taylor and Robert C. Johnson, Birmingham, Ala., assignors, by mesne assignments, to Southern Research Institute, Birmingham, Ala., a corporation of Alabama

Application January 24, 1947, Serial No. 724,012

6 Claims. (Cl. 73—7)

1

This invention relates to a yarn testing machine and has for an object the provision of apparatus of the character designated which shall be simple of design and operation and which shall be adapted to determine accurately the weaving quality of a yarn, its resistance to abrasion and its resistance to impact comparable to that to which it is subjected in a loom.

A further object of our invention is to provide a yarn testing machine which shall be adapted to determine selectively the resistance of the yarn to abrasion and to impact comparable to that to which it is subjected in a loom.

Briefly, our improved apparatus comprises mechanism which simulates the motions of a loom, without the complications of a loom, and provides means for collecting the fiber and other loom shed abraded from the yarn.

Apparatus embodying features of our invention is illustrated in the accompanying drawing forming a part of this application, in which

Fig. 1 is a plan view with certain parts partly broken away;

Fig. 2 is a side elevation;

Fig. 3 is a detail sectional view taken along the line III—III of Fig. 2, and

Fig. 4 is a detail sectional view of the reed carriage.

Referring to the drawings for a better understanding of our invention, our improved machine is mounted on four upright members 10, 11, 12, and 13 mounted on a base or floor member 14 and extending upwardly therefrom. The uprights are joined at the ends by cross members 16 and 17. Horizontally extending side frame members 18 and 19 extend rearwardly from the front of the machine to a point approximately midway the ends thereof where they are joined to depending vertical members 21 only one being shown. Other horizontal side frame members 22 and 23 are joined to the top of the members 21 and extend rearwardly therefrom to be joined to the upper ends of the vertical members 12 and 13.

At 24 we show a roller upon which the ends of yarn to be tested are wound, the roller 24 having a shaft 26, mounted in bearings 27 and 28, on the end frame members 10 and 11. A drum 29 is mounted on the end of the shaft 26 and a cable 31 is wound around the drum with one end secured thereto. The other end of the cable extends over a pulley 32, mounted on an upwardly projecting bracket 33 and has a weight 34 connected to its lower end for applying a predetermined tension on the yarn. At the opposite, or rear end, of the machine is mounted a take up roll 36 having a shaft 37, mounted in bearings 38 and 39, on the uprights 12 and 13. On one end of the shaft 37 is a worm gear 41 which is driven by a small, variable speed electric motor

2

42 having a worm 43 on the end of its shaft which meshes with the worm gear 41.

At 44 and 46 we show harness bearing the usual heddles and disposed on opposite sides of the depending upright frame members 21. The lower ends of the harness 44 and 46 are connected by means of a coil spring 47 which passes over a grooved roller 48 mounted on the lower end of the upright frame member 21. The upper ends of the harness 44 and 46 are supported respectively by treadles 49 and 51 having their forward ends pivotally connected to the upper cross frame member 16 at 52 and 53. The rearward ends of the treadles 49 and 51 are connected to the top of the harness at 54 and 56 by means of rods 54^a and 56^a carried in brackets at the top of the harness. Mounted on the treadles 49 and 51 are grooved follower rollers 57 and 58, which bear respectively on eccentrics 59 and 61, mounted on a cross shaft 62 having a drive sprocket 66 on one end thereof. The shaft 62 is mounted in bearings 63 and 64 on the forwardly extending side frame members 18 and 19.

At 67 and 68 we show, track members having upper convexly curved surfaces, which track members incline downwardly from the rear forwardly and which have their ends secured to the vertical members 21 and to the end members 12 and 13. Mounted above the tracks 67 and 68 and midway said tracks is a single rail 65 having its under surface concavely curved in parallelism with the upper convexly curved surfaces of the tracks 67 and 68. Mounted on the tracks 67 and 68 is a carriage comprised of L-shaped members 69 connected by cross rods 71 and 72 with rollers 73 and 74 on each side (only one side being shown) and which ride on the track members 67 and 68. In order to hold the carriage in place when subjected to the shocks of operation, we also provide flanged rollers 75 and 80 on the rods 71 and 72 which bear against the under side of the rail 65. Detachably mounted on the lower arms 77 of the carriage is a reed 78. The cross shaft 72 of the carriage is connected at its ends by links 79 and 81 to crank arms 82 and 82^a mounted on a shaft 83 extending across and journaled in the frame. A sprocket 85 is mounted on the shaft adjacent the crank arm 82.

Depending from the tracks 67 and 68 and directly behind the lower arms 77 of the carriage 69 are two links 94 (only one being shown) which are pivoted at 96 to swing freely from the tracks. The two links are connected by means of a cross rod 97. Threaded studs 98 are carried by the lower arms 77 of the carriage in position to strike the links 94 upon backward movement of the carriage as hereinafter described. Mounted on the rear vertical members 12 and 13 are a pair of stationary brackets 99, only one of which is

shown, and which are connected by a cross rod 101 which is disposed, as shown in Fig. 2 of the drawing, below the cross rod 97.

The harness 44 and 46 and the carriage carrying the reed 78, are driven by means of a variable speed motor 102 having a sprocket 103 on its drive shaft. A sprocket chain 104 passes from the sprocket 103 under the sprocket 85 and around the sprocket 66 to drive the harness. Any lint shed from the yarn being tested falls into a pan 106. It will be noted from the foregoing description that there are no projecting parts underneath the heddles 44 and 46 and reed 78 to obstruct falling lint or shed and that all means for imparting motion to the moving parts are located above the yarn in its passage through the apparatus.

In the operation of our improved apparatus, a suitable number of ends, say 500, are wound on the roller 24 with the weight 34 supplying a constant tension thereto. The ends are passed through the heddles in the harness 44 and 46 as in a loom, to provide a shed. The shedding motion is provided by the treadles 49 and 51 and cams 59 and 61 raising and lowering the harness 44 and 46. The ends pass from the heddles through the reed 78 and thence over the rod 97 and under the rod 101 to the takeup roll 36. The takeup roll being actuated by the variable speed motor 42 through the gearing described, draws the ends through the apparatus. The carriage 69 is reciprocated back and forth on the tracks 67 and 68 by means of the crank arms 82 and 83 and connecting links 79 and 81 so that the yarn is subjected to further abrasion in the reed 78. Each time the carriage 69 moves forward, the lower arm 77 moves away from the depending arm 94 allowing the arm 94 to swing forwardly a small amount. Upon rearward motion of the carriage, the studs 98 strike the arm 94, thereby subjecting the yarn to shock and elongation strain, simulating the beating up action in a loom. The degree of impact thus imparted may be varied by adjusting the studs 98. This action will cause any weak ends to break. As the ends travel through the apparatus, it will thus be seen that it is subjected to abrasive action and shock which will disclose any weakness in the yarn, its weaving qualities, and resistance to abrasion. Our improved testing machine is thus important in determining the relative values of various sizing compounds. Any fiber or other shed material abraded from the yarn falls into the pan 106 where it may be collected and weighed.

If it be desired to determine the resistance to impact only of the yarn, the harness 44 and 56 and reed 78 may be removed, in which case the yarn is passed from the roller 24 over the rod 97 and under the rod 101, whereupon at each reciprocation of the carriage, the studs 98 strike the links 94 and the yarn is subjected to impact only. Also, by stopping the harness motion and removing the links 94, the resistance of the yarn to abrasion only may be determined.

While we have shown our invention in but one form, it will be obvious to those skilled in the art that it is not so limited, but that it is susceptible of various changes and modifications, without departing from the spirit thereof, and we desire, therefore, that only such limitations shall be placed thereupon as are specifically set forth in the appended claims.

What we claim is:

1. In apparatus for testing yarn, means for

feeding a selected number of ends through the apparatus under tension, a swinging cross rod over which the ends pass, pivoted links in which the swinging cross rod is mounted, a stationary cross rod in the apparatus under which the ends pass, a reciprocatory carriage mounted in front of the pivoted links, and means on the carriage to strike the links at each reciprocation of the carriage.

2. In apparatus for testing yarn, means for feeding a selected number of ends through the apparatus under tension, heddles through which the ends pass, means to impart a shedding motion to the heddles, a reed carriage having a reed through which the ends pass, means to impart a reciprocatory and up and down motion to the reed carriage, means to collect lint and other material abraded from the ends in their passage through the apparatus, a swinging cross rod, pivoted links in which the swinging rod is mounted, a stationary cross rod beneath the swinging rod under which the ends pass, and means on the reed carriage to strike the links at each reciprocation thereof.

3. In apparatus for testing yarn, a supply roll on which a selected number of ends are wound, heddles through which the ends are passed, means to impart a shedding motion to the heddles, a reed through which the ends pass, a carriage on which the reed is mounted, means to impart a beating up motion to the carriage and reed, a swinging cross rod disposed at the rear of the reed over which the ends pass, pivoted links in which the swinging cross rod is mounted, a stationary cross rod beneath the swinging cross rod under which the ends pass, adjustable means on the reed carriage to strike the pivoted links at each beating up motion, means to collect lint and other material abraded from the yarn, and a variable speed take up roll to draw the ends through the apparatus.

4. Apparatus as defined in claim 3 in which the means for imparting motion to the heddles and carriage are disposed above the ends in their passage through the apparatus and in which the means for collecting lint abraded from the yarn is a pan located directly under the ends in their passage through the apparatus.

5. Apparatus as defined in claim 3 in which the carriage is mounted for reciprocation by means of rollers on convexly curved tracks.

6. Apparatus as defined in claim 3 in which the carriage is mounted for reciprocation by means of rollers on convexly curved tracks, and in which the carriage is held against displacement due to shocks of operation by means of a roller mounted on the carriage and bearing upwardly against a concavely curved rail mounted above the convexly curved tracks.
